United States Patent Office

Des. 187,561
Patented Mar. 29, 1960

187,561

BOTTLE

Ernest L. Du Pree, New York, N.Y., and Arthur Hewitt, Louisville, Ky., assignors to Schenley Industries, Inc., New York, N.Y., a corporation of Delaware

Application November 2, 1959, Serial No. 58,153

Term of patent 14 years

(Cl. D58—8)

Des. 187,561

PAGE 2

Fig. 2

The essential features of our design reside in the portions shown in full lines.

We claim:

The ornamental design for a bottle, as shown and described.
